UNITED STATES PATENT OFFICE

93,569

DESIGN FOR A RADIATOR CABINET

Richard H. Nelson, Moline, Ill., assignor to The Herman Nelson Corporation, Moline, Ill., a corporation of Illinois

Application July 9, 1934, Serial No. 52,507

Term of patent 7 years

To the Commissioner of Patents:

Be it known that I, RICHARD H. NELSON, a citizen of the United States, residing at Moline, in the county of Rock Island and State of Illinois, have invented a new, original, and ornamental Design for a Radiator Cabinet, of which the following is a specification, reference being had to the accompanying drawing, forming part thereof.

Figure 1 is a perspective view of a radiator cabinet showing my new design.

Figure 2 is a top plan view thereof.

I claim:

The ornamental design for a radiator cabinet, as shown.

RICHARD H. NELSON.
